UNITED STATES PATENT OFFICE.

FRANK A. ABENDROTH, OF NEW YORK, N. Y.

OIL-STOVE.

SPECIFICATION forming part of Letters Patent No. 325,471, dated September 1, 1885.

Application filed January 28, 1885. (No model.)

To all whom it may concern:

Be it known that I, FRANK A. ABENDROTH, a citizen of the United States, residing in the city, county, and State of New York, have 5 invented certain new and useful Improvements in Oil-Stoves, of which the following is a specification.

This invention pertains to certain improvements in the arrangement and construction of 10 the various parts of oil or gas stoves, as will appear in the annexed claims.

In the drawings, Figure 1 is a vertical section from the front to the rear, and also shows an outline of the tilting movements. Fig. 2 15 is a plan of the upper plate as applied to a stove of this plan. Fig. 3 is a plan of the drip-plate.

It is the purpose of my invention to improve the construction of oil or gas stoves, 20 whereby the drum portion may be tilted when the stove is in operation, for the purpose of trimming the wicks and replenishing the supply of oil.

It is also my purpose to so construct and 25 arrange the drip-recesses relatively to the burners that the overflowing or escaping oil will pass readily back into the oil-chamber.

It is a further object of my invention to improve the construction and arrangement of the 30 bridge-plate, placing it between the holes in the upper part of the stove-plate, and providing it upon its under surface with a deflecting-plate and loop, which serve as bearings as well as deflectors for the heat.

35 It is my purpose, finally, to provide novel means whereby the operator, when filling the oil-chamber, shall be able to determine readily when the oil has risen to the top of the reservoir in order that the inflow may be 40 checked at the proper point.

In the drawings, the reference-letter A designates the base of the oil-reservoir B. Upon the upper wall of this reservoir are mounted the wick-tubes C, of the ordinary type, with 45 attachments for operating the wicks, of any suitable form.

D represents the drum portion of the stove, of rectangular shape, and having its several dimensions about equal, so that the exterior 50 form is nearly cubical. It is provided with a

top plate, E, having a collar or depending flange, E', on its under side to fit upon the rim on the upper surface of the base-piece. This flange hooks over the center in front, and the rear end of the top piece, E, is supported by a 55 leg, F, hinged to the under side of said top piece, and serving not only as a support therefor, but as a lever to operate and support the same when tilted in the manner shown in Fig. 1, the angle of inclination being sufficient to 60 permit access to the wicks for the purpose of trimming. When the stove is fully heated and the burners require trimming, this mode of giving access thereto is a great convenience, as it avoids the necessity of removing the top 65 plate or the covers upon the holes.

G indicates the bridge-plate in the top plate. It does not differ materially from any other bridge-plate for stoves, serving as a support 70 between the holes, and when removed converting two holes into a continuous oblong opening. Said bridge-plate is provided with a depending flange or check-plate, H, at its rear end, to prevent the heat of the burners passing directly back and out of the rear 75 opening in the top plate, E, or from escaping when the valve or damper placed at the rear hole for an outlet for heated air is open.

The bridge-plate is also provided with V-shaped loops or prolongations K, extending 80 out toward the center of the holes L, and serving as supports for the covers or pots over the holes. Co-operating with the loops K are two other supporting devices for each hole. These are shown at M, and are cast on 85 the inner face of the heat space or flues, projecting upward to support the covers or the pots, and inclined toward the center of each hole, so that as the heat rises from the burners it is checked by these projections and driven up against the under side of the bottom of the pots or vessels upon the stove, for distribution and reverberation of the heat-currents.

By making the plate G removable from the plate E, as shown in the drawings, a pot can 95 be set directly over the heaters or burners, and thus the best and most immediate results of the heating action and capacity of the stove are obtained.

The drip-plate N beneath the burners or 100

wick-tubes is slightly inclined downward toward the rear of the stove, and has upon its surface ribs P, to guide the overflow from the burners toward the inlet at O, by which the 5 overflow is returned to the oil-reservoir.

Above the plate N is a loose cover-plate, N', provided with recesses at its corners to receive the supports of the air-box R, which fits closely around the burners, and at the same 10 time may be slipped upward off said burners.

At the back side of the oil-reservoir is placed a funnel, R', extending downward as far as the top of the oil-reservoir. This funnel consists of a triangular, circular, or otherwise shaped downwardly-dependant passage set in an opening in the top of the base portion of the stove, to which it is secured. It converges toward its lower end, which should not be extended beyond the bottom of the plate 15 N, and by this construction and arrangement the operator is enabled to see the oil as it enters the bottom of the funnel, and can therefore check the inflow at the proper point. The funnel is covered by a cap, which may be pivoted or hinged upon the base-piece in any suitable manner. By giving to it the converging form described, and terminating it at the top of the oil-reservoir, the operator is 20 enabled to see the oil clearly the instant it enters the bottom of the funnel.

What I claim is—

1. The loose bridge-plate G, provided with a depending rib, H, and the V-shaped projections K, in combination with the top plate of a stove, substantially as described. 35

2. The bridge-plate G, having the V-shaped projections, as shown, in combination with the upwardly-projecting deflectors M in the flues or flue-spaces, substantially as described.

3. In an oil-stove, the combination, with the 40 oil-chamber B, having loose cover N', of the inclined drip-plate N, having oil-conducting ribs P, and an oil-inlet to the oil-chamber at the lower end of the inclined drip-plate, said conducting-ribs converging to or meeting at 45 the said oil-inlet, substantially as described.

4. In an oil-stove, the depending flange or funnel-shaped passage set in an opening in the base-piece and leading into the oil-chamber, said passage converging toward its lower end, 50 and extending no farther than the top of said oil-chamber, whereby the supply of oil thereto may be checked at the proper point by the operator seeing the oil as it arrives at the lower end of said funnel, substantially as described. 55
